Des. 1208

William H. Smith, of Newport, R. I.
Letters Patent No. 1208. Dated July 21, 1860.

mmmm

The schedule referred to in these Letters Patent and making part of the same.

mmmm

To all whom it may concern:

Be it known that I, William H. Smith, of Newport, in the County of Newport and State of Rhode Island, have invented or produced a new & original design for a Stove, and I do hereby declare that the following is a full, clear, and exact description of the same, reference being had to the annexed drawings making a part of this Specification, in which:

Figure 1. is an elevation of a Stove showing my design.

Figure 2. a detached plan or top view of the base.

Similar letters of reference indicate corresponding parts in the two figures.

This design for a Stove relates to the top, the door and frame, and the base and feet. The top is formed of three external parts, to wit; an Eagle, slatted dome, and annular support which surrounds the radiator.

The Eagle A, is of the form commonly termed the "Spread eagle" and it stands on a semi-sphere a, at the apex of the slatted dome B, as shown clearly in figure 1. The lower part or base of the dome B, projects slightly outward and terminates in a rim b, which is connected with the slats c, of the dome, the slats being beaded, each having three beads a broad central one $\frac{1}{2}$ and a narrow one $\frac{1}{4}$ at each edge. The annular support C, of the dome has a double inclined exterior d, e. The surface d, being provided with "set" ornamental projections 2, 3, 4 and 5, and the surface e, provided with the stars 6.

The door frame D, figure 1, has a corner sprig f, at each angle, and a statuette g, at each side, and the door E, has a vine h, around its edge with a panel i, having two upper corner ornaments j, j.

The base of the Stove is formed of three parts, the upper part F, is of cyma-reversa and cyma-recta form and has small set ornaments j, and k on it. The draught register G, is provided with ten set ornaments q, q. The lower part H, of the base, is provided with set ornaments l, extending all around it and also beads 11, 12.

The base is supported by feet K, which have a narrow scolloped border l, extending all around them and within this border there are

Wes. 1208

set ornaments on.

I claim as new and desire to secure by Letters Patent.

The configuration herein shown and described of the top, —
door, and frame, base and feet, to form a new and ornamental design for a Stove.

Witnesses.
